UNITED STATES PATENT OFFICE.

JOSEPH M. THORPE, OF SAN FRANCISCO, CALIFORNIA.

FURRING NAIL.

Application filed January 18, 1926. Serial No. 81,997.

The present invention relates to furring nails such as are used for spacing a wire netting from the wall of a house for the purpose of applying plaster thereto.

5 The principal object of the invention is to provide a furring nail that is used in construction, will not tear the paper against which it rests and is formed in such a manner that the spacing element is firmly held 10 to the nail penetrating the same so that the whole device may be conveniently handled as a single unit.

Further objects and advantages of my invention will appear as the specification 15 proceeds.

The preferred form of the invention is illustrated in the accompanying drawing in which

20 Figure 1 shows a side view of my furring nail.

Figure 2 an end view of the same.

Figure 3 a top plan view of the spacing element before the nail is driven there-through.

25 Figure 4 a top plan view of the spacing element after a nail has been driven through the same and been removed.

Figure 5 an assembly view of my furring nail in place on a wall.

30 Figure 6 a side elevation of two dies by means of which my furring nail may be made.

Figure 7 an end view of a modified form 35 of furring nail.

While I have shown only the preferred form of the invention I wish to have it understood that various changes or modifications may be made within the scope of the claims hereto attached without departing 40 from the spirit of the invention.

My furring nail 1 may be made of a short strip of metal the central portion of which is bent into an arcuate form 2 shown in the drawing while at the ends it terminates in 45 flat wings 3 which before application to the wall are slightly inclined toward the latter as appears particularly well from Figure 1.

In the center of the arc there is provided a hole 4 from which depends a short sleeve 50 6 having a narrow mouth 7 of oval form as illustrated in Figure 3.

When a nail is forced through this sleeve the mouth of the same stretches or flows to the form of the nail without causing a fracture 55 in the formation of the sleeve whereby greater frictional contact is created between

the nail and the sleeve. After a nail has been driven through the sleeve it looks in top plan view as illustrated in Figure 4, the oval mouth having been rounded and the 60 sleeve being of substantially the same length all around the nail without showing any longitudinal splits.

This form of hole or sleeve is brought about by the manner in which the device is 65 made and to explain this feature reference is made to the dies 8 and 9 shown in Figure 6. It will be noted that the arcuate section in the strip of metal is formed between a male die 11 and a female die 12 and that a 70 short punch 13 is placed inside of the latter in such a manner that the metal is first curved into arcuate form before the punch becomes active on the material. The latter being thus under tension the punch 75 causes a longitudinal split in the same rather than a round hole and this longitudinal split develops into the sleeve with an oval mouth 80 illustrated in Figure 3. The further operation of forcing a slightly larger nail through the mouth causes the metal to stretch in the manner previously described.

Along the side edges of the arcuate portion of the spacing element are provided 85 flanges 14 which are sufficiently far apart to accommodate between the same the nail head 16 in the manner illustrated in Figure 5 and the strands of wire 17 between the nail head and the top of the spacer. In this manner the nail head does not project 90 beyond the top edges of the flange and does not interfere in any manner with the operation of the plasterer applying the material to the wall.

A further advantage gained by the particular construction shown in the drawing 95 is that the flange may be used for picking up the wire, the device being first tilted to introduce one of the flanges underneath the wire strand and then tilted back into a 100 straight position whereby the wire strand is caught between the flange and the nail. When a blow with the hammer is executed 105 the nail is driven into the wood and the two wings separate slightly riding along the paper usually interposed between the wall and the spacer. Any tendency of the wings to cut into the paper is met by the extreme 110 lightness of the taper of the wings which causes the latter to glide over the paper and also by the yielding quality of the latter which stretches slightly before tearing.

As a particular advantage of the arc form of the furring nail, it might be mentioned that the plaster may freely enter under the arc from both sides and close in on the nail 5 so as to prevent any leakage of water along the nail to the wall surface.

If it is desired to strengthen the structure of the spacer the latter may be slightly more contracted as shown in Figure 7 in which 10 the sides 18 of the spacer are vertical and of considerable length while the arc is shortened as shown at 19. This form will withstand a heavier blow than that previously described. It should also be noted 15 that due to the shortened arc the tubular extension becomes longer, giving greater frictional surface to hold the nail.

I claim:

1. A furring nail of the character described, comprising an arcuate metallic spacer formed with a perforation in the center thereof and with a sleeve depending from the margin of the perforation, the

sleeve having a narrowed oval mouth causing the metal to stretch to the form of a nail 25 driven through the sleeve without being fractured.

2. A furring nail of the character described comprising an arcuate spacer terminating in flat wings at the ends made for 30 contacting engagement with a wall, the wings being inclined slightly toward the wall and causing the spacer to spread without tearing interposed paper when the spacer is struck.

3. A furring nail of the character described, comprising a metallic arcuate spacer formed with a perforation in the center thereof and with a sleeve depending from the margin of the perforation, the sleeve 40 having a narrowed mouth causing the metal to stretch to the form of a nail driven through the sleeve without being fractured.

In testimony whereof I affix my signature.

JOSEPH M. THORPE.
